UNITED STATES PATENT OFFICE.

STEPHEN G. SINGLETON, OF BURKE, IDAHO.

TOOTHPICK-HOLDER.

1,311,625.

Specification of Letters Patent. Patented July 29, 1919.

Application filed March 26, 1919. Serial No. 285,304.

To all whom it may concern:

Be it known that I, STEPHEN G. SINGLETON, a citizen of the United States, and a resident of Burke, in the county of Shoshone and State of Idaho, have invented certain new and useful Improvements in Toothpick-Holders, of which the following is a specification.

My invention relates generally to tooth pick holders, and more particularly to a tooth pick holding and dispensing device, the principal object of my invention being the provision of a tooth pick container which will keep the tooth picks in a perfectly sanitary condition, free from dust, insects, and the like, and also from contamination during the extraction of one or more of the picks for use.

Another object of my invention is the provision of a device that will be simple in construction, easy to operate, and economical of manufacture, as well as one which will hold the tooth picks in convenient position for extraction by the fingers, without necessitating the touching of any of the tooth picks except the one selected for withdrawal.

A further object of the invention is the provision of a tooth pick container which will be especially useful in public eating places, such as restaurants, hotels, cafes, and the like, where a large number of people use tooth picks, and one which will obviate fingering of the main supply of picks in the selection of a single pick, as in the case of open tooth pick containing jars or dishes commonly employed at present.

Generally speaking, my invention proposes a tooth pick container in the nature of a shaker, from which, by shaking movement of the container, tooth picks are partially discharged, in such a manner that individual picks are projected a portion of their length beyond the limits of the container in order that they may be grasped and fully extracted individually by the fingers.

In the accompanying drawing illustrating my present invention and forming a part of the specification,

Figure 1 is a perspective view of my improved tooth pick shaker, illustrating the partial discharge of individual tooth picks for removal by the fingers.

Fig. 2 is a longitudinal section through the tooth pick shaker,

Fig. 3 is an end view looking at the discharge cap, and

Fig. 4 is a face view of the discharge controlling member removed.

Referring now to these figures, my invention proposes a tooth pick holder including a cylindrical container 10, which is closed at one end 11, and which is preferably of a diameter adapted to receive and retain a quantity of tooth picks in upright position, that is, with their longitudinal axes parallel to the longitudinal axis of the container 10. This container 10 is preferably threaded as at 12, adjacent to its open end, for reception of the threaded inner portion 14 of the flange 15 of a cap 16, which cap covers the open end of the container 10 and is provided with a series of radial slotted openings 17, each of a size adapted to permit of free discharge therethrough of a tooth pick.

The flange 15 of the cap 16, which is threaded at 14 at one edge, is provided with an annular groove internally thereof, adjacent to and around the edge of the cap 16, this groove being indicated at 18 in Fig. 2 and providing for the reception of a discharge controlling disk 19, formed of some flexible elastic material, preferably rubber, which is disposed against the inner face of the cap 16 as shown in Fig. 2 and properly associated with the cap, and which is provided with radial slits 20 which align with the slotted opening 17 of the cap although they are of considerably reduced area as compared to the slotted openings 17, the purpose of the slits being to admit of but partial movement of the picks therethrough.

Tooth picks are usually reduced at their ends, and their reduced ends may pass through the slits 20 of the controlling disk 19, by shaking the container 10 in the direction of its length, so as to produce a partial discharge of individual toothpicks as seen in Fig. 1 at 21. In this way, the tooth picks are individually moved to positions permitting them to be readily grasped and individually withdrawn without danger of contamination of the remaining tooth picks of the supply within the container 10, it being obvious that the tooth picks will be yieldingly grasped and held by the discharge controlling disk 19 for the above purpose.

It is further obvious that by virtue of the discharge controlling member 19 with its

comparatively minute slits for the discharge of the tooth picks, dust, insects, and other matter will be excluded from the interior of the container so that the main supply of 5 tooth picks can be maintained in sanitary condition at all times.

It is of course to be understood that the cap 16 will be formed of metal or some comparatively inflexible material so that the 10 flexible elastic discharge controlling disk 19 within the cap will be effectively protected at all times.

I claim:

1. A tooth pick holder in the nature of 15 a shaker, consisting of a casing having a cover at one end provided with openings admitting of passage of the tooth picks therethrough, and means in connection with said cover to yieldingly hold the tooth picks in 20 position partially through the cover open-

ings during the discharge of the tooth picks, said last named means consisting of an apertured disk of an elastic material supported along the inner surface of the cover and protected by the latter.

2. A tooth pick holder in the nature of a shaker consisting of a casing having a cover at one end provided with openings admitting of passage of the tooth picks therethrough, and a flexible disk within the casing adjacent to the said cover, having openings of reduced area with respect to the openings of the cover and aligned with the latter, the openings of the flexible disk being of a width less than the greatest diameter of the tooth picks within the casing.

STEPHEN G. SINGLETON.
